CLAIM

The ornamental design for a storage rack, as shown and described.

DESCRIPTION

FIG. 1 is a perspective view of a storage rack showing my new design;

FIG. 2 is a perspective view thereof from another angle;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2;

and,

FIG. 12 is a partial enlarged view of portion 12 in FIG. 2.
